[57] CLAIM

The ornamental design for a knife handle, as shown.

DESCRIPTION

FIG. 1 is a perspective view of a knife handle showing our new design; the broken line showing of a knife blade is for illustrative purposes only and forms no part of the claimed design;

FIG. 2 is a front elevational view thereof;

FIG. 3 is a rear elevational view thereof;

FIG. 4 is a top view thereof;

FIG. 5 is a bottom view thereof;

FIG. 6 is a right side elevational view thereof; and,

FIG. 7 is a left side elevational view thereof.
